Primary Examiner — Amber R Stiles(74) *Attorney, Agent, or Firm* — METIS IP LLC(57) **CLAIM**

The ornamental design for a pet ladder as shown and described.

DESCRIPTION

FIG. 1 is a front view of a pet ladder with our new design; FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view of;

FIG. 8 is another perspective view thereof;

FIG. 9 is an enlarged view of detail A in FIG. 3;

FIG. 10 is another enlarged view of detail B in FIG. 7; and, FIG. 11 is another perspective view of the pet ladder when the ladder is folded.

The dot-dash broken lines in FIG. 3, FIG. 7, FIG. 9 and FIG. 10 are for the purpose of annotating the enlarged views only and form no part of the claimed design.

1 Claim, 11 Drawing Sheets(56)
